United States Patent

Des. 237,933

Patented Dec. 9, 1975

237,933

MIRROR OR PICTURE FRAME

Oliver Farley, 1428 Sterling Place,
Brooklyn, N.Y. 11213

Filed Apr. 5, 1973, Ser. No. 348,369

Term of patent 7 years

Int. Cl. D6—07

U.S. Cl. D6—244

FIG. 1.

FIG. 2.

FIG. 3.

FIG. 4.

FIG. 6.

FIG. 5.

FIG. 1 is a front and top perspective view of a mirror or picture frame showing my new design;

FIG. 2 is a left side elevational view;

FIG. 3 is a right side elevational view;

FIG. 4 is a top plan view;

FIG. 5 is a front elevational view; and

FIG. 6 is a front elevational view of another embodiment of a mirror or picture frame showing my new design, wherein the top and bottom members are of equal height and the baseball representations are touching each other.

The rear of the frame is plain and unornamented.

I claim:

The ornamental design for a mirror or picture frame, substantially as shown and described.
